UNITED STATES PATENT OFFICE

CYRIL A. COLLINS, OF DEARBORN, MICHIGAN

AUTOMATIC WATER FEEDER

Application filed January 16, 1931. Serial No. 509,222.

This invention relates to an appliance or structure which may be conveniently referred to in the following specification and claim as an automatic water feeder and it has more particular reference to an especially designed contrivance developed to control the supply of water to a humidifier of the type used in association with present-day hot air furnaces.

These humidifiers are of diversified construction according to the particular kinds of furnaces with which they are used. Generically considered however, the humidifier embodies a tank and a cover with means for supplying water to the tank to be employed for humidifying purposes.

The object of the present invention is to provide a simple, economical, and dependable, float-actuated control valve and associated details, all of which are embodied in a novel cover for the tank.

In carrying the inventive conception into practice, I have evolved and produced a feasible arrangement of details characterized by a cover for the humidifier tank wherein said cover is provided with a dome-like projection with which the water supply pipe is connected, an especially designed valve being associated therewith and said valve being under the control of float actuated means which depends into the tank.

In preparing the drawings to disclose the selected details and association and arrangement thereof, I have omitted the tank as it will vary in shape, size and proportions according to the furnace with which it is used. Moreover, I have merely disclosed an especially formed casting which constitutes the cover for the tank and which in practice will vary in shape and proportion. The general principle of construction is the same irrespective of the particular tank and cover.

In the drawings:

Figure 1 is an elevational view of an assembly developed in accordance with my invention.

Figure 2 is a top plan view thereof with the dome-like water inlet in section.

Figure 3 is a longitudinal view through the valved water feed or inlet.

Figure 4 is a bottom plan view of the structure seen in Figure 1.

Figure 5 is a sectional view through the valve element per se.

Figure 6 is a top plan view of the float. 55

Figure 7 is an elevational view of the float.

The general arrangement and assembly may be seen in Figure 3 when compared with the other views. In this figure the casting is 60 generally represented by the numeral 8 and this is shaped to form a cover for the humidifier tank (not shown). This particular cover is provided with a marginal flange 9, a reinforcing rib 10, and adjacent one end it is 65 formed with an integral upstanding dome-like projection 11 which constitutes the water delivery or feed means.

As seen in Figure 2, this is formed on one side with a nipple 12 designed to accommodate a water delivery pipe (not shown). As observed in Figure 3, this projection 11 is of hollow construction to telescopically accommodate a novel fitting 13. This part 13 includes a tubular body portion 14 projecting 75 into the connection 11 and having its upper end provided with a strainer or screen 15.

The lower end portion thereof is provided with a flange carrying a packing ring 16 to provide a watertight connection. The central bore of this fitting is shaped intermediate its ends to provide a valve seat with which the head 16 of the valve element 17 is engageable. The stem of the valve is carried by a rocker 18 which is pivoted as at 19 between a pair of depending lugs 20 on the underside of the cover. 80

The stem is also provided with an annular gasket or ring 21 which directly co-operates with the valve seat. The rocker is swingably 90 mounted at a point intermediate its ends and one end portion 21' fits telescopically into a tubular rod or pipe 22 which in turn extends into a socket 23 formed in the float 24. It is evident that this float is adapted to depend 95 into the water contained in the humidifier tank.

When the water is at the proper level, the float closes the valve. When the water recedes to an abnormal low level, the float drops 100

and opens the valve to permit replenishment of the tank. The dimensions and proportions of parts are such as to permit this automatic opening and closing of the valved supply line at predetermined intervals of time.

The principal details of the structure are as follows. The cover 8 is of suitable shape, size and proportions, and by preference includes an integral dome-like hollow connection or extension 11 which is elevated and provided with a nipple to accommodate the watersupply pipe (not shown).

On its underside and located beneath this extension 11 are hanger ears or lugs 20 which serve to suspend the balanced rocker, said rocker being provided on one end with a valve element and on the other end with a tubular arm 22 carrying the remote float. The especially designed packed fitting which projects into the part 11 is important. It is such as to facilitate assembly and constitutes a unit with the rocker, valve element, seat and packing means as is evident from Figure 3.

It is thought that the description, taken in connection with the drawings will enable a clear understanding of the invention to be had. Therefore, a more lengthy description is thought unnecessary.

While the preferred embodiment of the invention has been shown and described, it is to be understood that minor changes in shape, size, and rearrangement of details, coming within the field of invention claimed may be resorted to in actual practice if desired without departing from the spirit and scope of the appended claim.

I claim:

In combination with a tank cover having a dome thereon, with a nipple extending from the dome and in communication therewith, a plug removably fitting in the interior of the dome with an enlarged part extending from the lower face of the cover, a gasket located between the said enlarged part and the under face of the cover for forming a liquid tight joint between the plug and the dome, a screen in the upper part of the plug, a valve seat formed in the plug, a valve having a stem projecting from the plug, a gasket on the valve having an enlarged upper part forming a seat with the lower part for engaging the valve seat, ears depending from the cover, a rocker arm pivoted between the ears having one end engaging the lower end of the valve, a tube fitting over the other end of the rocker arm, and a tank forming a float connected to the opposite end of the tube.

In testimony whereof I affix my signature.

CYRIL A. COLLINS.
